GAS HEATER

Filed April 11, 1925

INVENTOR
A. A. SMITH
BY *Munn & Leo.*

ATTORNEYS

UNITED STATES PATENT OFFICE.

ALLAN A. SMITH, OF CHICAGO, ILLINOIS.

GAS HEATER.

Application filed April 11, 1925. Serial No. 22,387.

My invention relates to improvements in gas heaters, and it consists in the constructions, combinations and arrangements herein described and claimed.

5 An object of my invention is to provide a gas heater in which the heated air instead of largely rising as with an ordinary gas heater is distributed laterally around.

10 A further object of my invention is to provide a device of the type described having means operated by the ascending current of hot air for causing such lateral distribution of the heated air current.

15 A further object of my invention is to provide a device of the type described which is simple in construction but positive in action, and which does not require any attention for its efficient operation.

20 Other objects and advantages will appear in the following specification, and the novel features of the invention will be particularly pointed out in the appended claims.

25 My invention is illustrated in the accompanying drawings forming part of this application, in which—

Figure 1 is a side view of the device, certain parts being broken away or shown in section,

30 Figure 2 is a section along the line 2—2 looking in the direction of the arrows, and

Figures 3 and 4 are enlarged detail views of portions of the device.

35 In carrying out my invention I provide a tapered metal shell 1, open at its bottom and at its top. At the bottom of the shell is an exterior ring 2, and to this ring are secured legs 3. These legs, as will be observed, are bent outwardly and continue upwardly as shown at 3^x. The purpose of the extensions 3^x, which are spaced from the shell 1, is to afford a holding means for the flexible gas tube 7. When the heater is not in use this gas tube may be wound around the bottom portion of the shell and the coils will be held in position by means of the extensions 3^x. Below the bottom of the shell is a plate 4, which serves as a shield, as for instance, where a burning match is dropped through the bottom of the heater, in which case it would be caught by the plate 4 and it would prevent the burning of the carpet or floor.

40 At 5 I have shown the valve control of a burner of any suitable type, while within the shell are the inner burner portions 6,

The burner may be attached to any suitable source of gas, as by the tube 7.

At the top of the shell 1 is a ring 8 and below this ring is a bearing member 9 which is secured upon a rod 10 extending through and being fastened to the shell 1. Secured to the bearing member 9 is a rod 11 which also passes through the shell 1, being secured thereto by means of nuts 12 on either side of the shell.

45 The bearing member 9 has extending upwardly from its center a bearing pin 13 (see Figure 4). Secured to the ring 8 are L shaped brackets 14 and carried by the brackets is a frame 15, the central portion 16 of which has an adjustable bearing screw 17, the position of which may be adjusted by the nuts 18.

50 A shaft 19 is provided and to this shaft is secured a propeller 20 by means of nuts 75 21. The propeller is preferably a circular disc having blades punched therefrom, the blades being disposed in angular relation with the plane of the disc, as shown in the drawing. Above the propeller and secured to the shaft 19 are vanes 22. It will be observed that the bottom portions of these vanes are curved for a purpose hereinafter explained.

55 The shaft 19 has a reduced extension 23 arranged to enter a recess 24 in the adjusting screw 17. The lower end of the shaft 19 has a recess 25, a steel ball being fixedly held therein and being arranged to rest on the bearing pin 13 of the bearing 9.

60 From the foregoing description of the various parts of the device, the operation thereof may be readily understood. The legs 3 raise the shell 1 from the floor so as to provide a free circulation of air underneath. 95 The burner being lighted heats the air within the shell which then rises and is concentrated by means of the tapering shell. The rising current of hot air impinges on the blades of the propeller 20, thus rotating it. 100 This rotation is easily effected because the shaft 19 upon which the propeller is borne turns on the ball 26, which in turn rests on the pin 13, the upper end of the shaft being held in the recess 24. The turning of the shaft 19 turns the vanes 22 and these cause the lateral currents of air to be thrown out radially. Thus the heat which would otherwise rise is spread out so that anyone in the vicinity will get the benefit thereof in addi- 110

tion to getting the heat radiated from the shell 1. The device is therefore particularly efficient in delivering heat where it will do the most good; that is to say, largely in a lateral direction.

In order to transport the device, I provide a handle 27 which may be used even when the stove is hot.

I claim:

- 10 1. A gas heater comprising a tapered shell, means for supporting the shell, a burner carried within the shell near the bottom thereof, a bearing support near the top of the shell, a frame carried by the shell, a vertical shaft journaled between said frame and said bearing support; a horizontally dis-
- 15

posed propeller carried by said shaft, and vanes carried by said shaft above said propeller for driving heated air in a direction at right angles to the shaft.

20 2. A gas heater, comprising a tapered shell, means for supporting the shell, a burner carried within the shell near the bottom thereof, and a fan disposed at the top of the heater, said fan being mounted on a vertical axis and being driven by the concentrated stream of air from the tapered shell and having vanes arranged to throw the air at right angles to the central longitudinal axis of the shell.

ALLAN A. SMITH.
